R. Wesley Mellow, Clayton, Mo., assignor to
Liberty Foundry Co.

Continuation of abandoned design application Ser. No.
230,545, Feb. 29, 1972. This application Apr. 22, 1974,
Ser. No. 462,746

Term of patent 14 years

Int. Cl. D7—08

U.S. Cl. D7—206

FIG. 1.

FIG. 2.

FIG. 4.

FIG. 3.

FIG. 1 is a perspective view of a swinging grate for inside fireplace showing my new design;

FIG. 2 is an enlarged left end elevational view thereof;

FIG. 3 is an enlarged bottom plan view of the grate, the lower support being omitted for purposes of disclosure;

FIG. 4 is an inverted left end view of the grate as seen in Figure 3.

The standing grate is shown in broken lines in FIGS. 1 and 2 for illustrative purposes only.

This is a continuation of design application Ser. No. 230,545, filed Feb. 29, 1972 and now abandoned.

I claim:

The ornamental design for a swinging grate for inside fireplace, as shown and described.
